UNITED STATES PATENT OFFICE.

JESSE L. DONAHOO, OF MINNEAPOLIS, MINNESOTA.

LIQUID-FUEL BURNER.

Application filed October 1, 1924. Serial No. 741,044.

My invention has for its purpose to provide an improved liquid fuel burner which may be used in combination with furnaces, hot water heaters, stoves, etc.

5 To disclose the same, the following description is made in connection with the accompanying drawings in which like reference characters refer to the same parts throughout the different views, and in which, 10 Fig. 1 is a view in side elevation of a portion of a furnace, with my burner applied, the walls of the furnace being broken away to show the burner;

15 Fig. 2 is a plan view of my improved burner;

Fig. 3 is a vertical section taken on the line 3—3 of Fig. 2; and

Fig. 4 is a vertical section taken on the line 4—4 of Fig. 2.

20 Referring to the drawings, A denotes a portion of a standard furnace having a draft opening B in the lower portion thereof. Above the draft opening, the furnace proper is sealed by a partition C of non-inflammable material which is preferably supported by the grate bar supports of the furnace, but may be supported by any other suitable means.

25 A rectangular opening is formed in the partition C over which a base plate 5, preferably of rectangular shape, fits, said plate resting upon the partition C and held in engaging position with the partition by means of depending flanges 6 which abut

30 against the sides of the opening in the partition. The plate 5 is provided with a number of grooves 7 at either end and either side thereof. A circular portion is cut in the center of plate 5 into which the bowl 8 fits.

35 The bowl 8 is positively held in engagement with plate 5 by means of depending lugs 9 formed on the bottom of the bowl, said lugs fitting into corresponding notches cut in the circular edge of plate 5. Plate 5 is formed 40 with ellipse-like openings 10 toward each end of the plate communicating directly with the ash pit of the furnace.

45 The bowl 8 is formed with an upstanding conical cylindrical burner head 11, the upper side of which is cast into a series of concentric circular grooved flanges. The bowl 8 is substantially circular in form with half elliptical indentations at two opposite points on the edge thereof. The bowl is curved 50 upwardly outward from the base of the burner head 11. A threaded fuel opening 12

is formed in the center of the burner head 11 through which fuel conduit 13 fits. An overflow drainage pipe 14 fits into a threaded drain opening 15 on the side wall of the 60 bowl. An inverted substantially U-shaped air manifold 16 is placed over the bowl having a central air discharge outlet situated immediately over the fuel inlet 12, the outlet reaching down almost to the top of 65 the discharge end of the fuel conduit. The hollow arms of the manifold are formed substantially ellipse shape in cross section at their lower portions and taper upward to substantially a circular form in cross section 70 meeting together at the central discharge outlet. The joining arms form a substantially V-shaped portion at the inner top of said manifold, which acts as an air deflecting plate to direct air from said arms downwardly to the discharge outlet. The lower ends of the arms fit immediately over the elliptical openings 10 in plate 5 and have communication with the ash pit of the furnace. The arms fit within the half elliptical indentations on bowl 8 and hold the bowl 8 from removal from its seat on plate 5. The arms themselves are, in turn, held in positive engagement with plate 5 by means of upstanding flanged lugs 17 formed on the plate 5. The fuel inlet pipe 13 will be joined by suitable connections to a fuel supply tank and the supply of fuel will be regulated by any of a number of well known means, such as by a hand valve 18. 90

The operation of the burner is as follows:

A supply of liquid fuel will be allowed to run through the fuel inlet conduit 13 down over the grooved burner 11 and into the bowl 8 filling each successive groove as it 95 runs down. A small lighted piece of paper will then be thrown into the bowl. The burning of the paper will generate sufficient heat so that the crude oil or other liquid fuel used will light. Air will be supplied to the burner through the medium of the air manifold 16 and will be projected downwardly upon the fuel. The burner head 11, bowl 8 and manifold 16 will soon become heated red hot. The hotter the burner gets, the hotter 100 will become the air manifold, and, consequently, the air therein. As the air gets hotter the greater will be the draft through the manifold, due to the faster movement of the air, the expansion of heated air and the 110 tapering shape of the manifold arms. After the burner has been burning for a short time

and heated sufficiently, almost all of the hydro-carbon fuel will be generated into gas immediately. The amount of heat desired may be easily obtained by regulation of the fuel supply conduit through any well known thermostat system. Both the burner and the lower portions of the bowl are constructed of very heavy metal of considerable thickness so that they will hold the heat for a long time and reflect, conduct and radiate the same. This heat holding feature is one of the chief factors in obtaining the high efficiency of applicant's burner.

The burner may be very quickly installed in any type of furnace, hot water heater or stove. By forming the plate 5 with grooves 7 along each end and side, the plate can be made to fit various sized furnaces, etc. If a smaller sized plate is desired than the regulation size, the plate may be placed with an end or a side along a straight edge so that the straight edge will aline with one of the grooves 7 and the outer side of the groove hammered until it breaks off. Due to the grooves, the edge will remain straight after a part has been broken therefrom. Although plate 5 is illustrated as of rectangular shape, any other shaped plate may be used having a series of grooves formed thereon adjacent its edges parallel to or concentric with its edges. This circular type of plate is particularly adapted for use with round furnaces.

By extending the inlet conduit 13 above the burner head 11, and to a point almost within the air manifold 16 and directly below it, the fuel inlet is prevented from being clogged with carbon, dirt or grease and a heavy flow of fuel is thereby secured at all times. It is found that the ashes of any

paper that may be used in starting the burner are quickly broken up and carried up the chimney, leaving the bowl clean. At about zero degree F. weather it is found that after the burner has become fully heated, all the fuel supplied will become generated into a combustible gas shortly before it flows down onto the bowl 8.

In actual practice, the burner has been found to heat twenty-four hours in every day with great efficiency in all weather. The parts are few and simply constructed and may be easily made. The burner is inexpensive to operate and practically self cleaning.

It will, of course, be understood, that various changes may be made in the form, details, arrangement and proportions of the various parts without departing from the scope of applicant's invention which, generally stated, consists in the structure shown and described and set forth in the appended claim.

What is claimed is:

A liquid fuel burner comprising a base plate, a bowl positively resting on said plate, said bowl having a central burner head 65 formed integral therewith, said bowl being substantially circular in shape having oppositely disposed semi-elliptical indentations on the edge thereof, and an air supply manifold having a central discharge opening 70 above said burner head, and upwardly tapering hollow arms fitting over openings in said plate and into the semi-elliptical indentations on said bowl, said arms being positively held in engagement with said plate. 75

In testimony whereof I affix my signature.

JESSE L. DONAHOO.
